UNITED STATES PATENT OFFICE

HARRY W. PROTZELLER, OF EAST CHICAGO, INDIANA, ASSIGNOR TO O. F. JORDAN COMPANY, OF EAST CHICAGO, INDIANA, A CORPORATION OF INDIANA

RAILWAY MAINTENANCE AND CONSTRUCTION CAR

Application filed April 22, 1929. Serial No. 356,915.

This invention relates to improvements in railway maintenance and construction cars and it consists in the matters hereinafter described and more particularly pointed out in the appended claims.

The primary object of the invention is to provide in a car of this kind, improved means carried by and adapted for cooperation with the main spreader wing for forming a ditch of the desired depth parallel with the track without disturbing the distance recognized as the usual standard between the track and inner corner of the ditch.

Still another object of the invention is to provide a simple and efficient ditching blade construction carried on the rear side of the main spreader wing and so disposed thereon for projection and retraction in a plane other than perpendicular that the depth of the ditch being made may be changed at will even while the car is moving.

These objects of the invention as well as others together with the many advantages will more fully appear as I proceed with my specification.

In the drawings:—

Fig. 1 is a view in side elevation of the front end portion of a railway maintenance and construction car embodying my invention.

Fig. 2 is a view in elevation on an enlarged scale of the rear side of the spreader wing, in which the preferred form of the invention is embodied.

Fig. 3 is a longitudinal sectional view through the same as taken on the line 3—3 of Fig. 2.

Fig. 4 is a vertical sectional view through the spreader wing as taken on the line 4—4 of Fig. 2.

Fig. 5 is a diagrammatic view showing a conventional cross section of a ditch made by my improved construction.

Fig. 6 is a view in rear elevation of the ditcher blade embodied in my improved construction.

Fig. 7 is a vertical section view through the ditcher blade as taken on the line 7—7 of Fig. 6.

Fig. 8 is a view in rear elevation of the

carrier plate for the ditching blade, with parts broken away to more clearly show the construction thereof.

Referring now in detail to that embodiment of the invention illustrated in the accompanying drawings, 1 indicates as a whole the body of the car provided at both ends with wheels 2 for travel upon the rails of a railroad track 3. At the front end of the car is a V shaped plow 4 and at each side of said front end of the car is a plow wing or apron 5. Said plow and its side wings are vertically adjustable by means of an upright pneumatic cylinder 6 disposed at the front end of the car body.

Rising from each side of the car body and its underframing, at substantially the rear end of the plow wings 5—5 is an upright wing post 7 and above the decking of the body, to the rear of the posts is an operator's cab 8. The top end of each wing post is braced by bars 9 from an associated standard 10 rising from the body, just to the rear of the front plow 4.

Mounted on the bottom portion of the wing post for a vertical as well as a turning movement, is a hinge plate 11 and on the top portion of the post is a collar 12, also mounted for a vertical and a turning movement. 13 indicates a horizontally disposed boom fixed at its inner end to the collar 12 and the outer end of said boom is supported from the hinge plate 11 by a brace 13^a.

14 indicates as a whole the inner or main ballast spreader wing, there being one of such wings associated with each wing post. Said wing comprises a skeleton like body 15 and a front plate 16 and on the rear side of said body at its inner end is a plate 16^a. These two plates provide smooth surfaces on both sides of the inner end of the wing which is embraced by the hinge plate 11 and is pivoted thereto as at 17 for a swinging movement about a horizontal axis. Such swinging movement is imparted to the wing by means of a double acting power cylinder 18 pivoted at its top end to the outer end of the boom 13. To the other end of said cylinder is secured a yoke 19 including a tubular body 20. Telescopically slidable in said body is a tube

21 which is operatively connected at one end to the usual piston in the cylinder and is operatively connected at its other end to the wing 14 by means of front and rear bracket plates 5 22.

When air under pressure is admitted to one end or the other of the cylinder 18, the tube 21 telescopes inwardly or outwardly of the body 20 so as to impart a raising or lowering 10 swinging movement to the wing 14 about its pivotal connection 17 with the hinge plate. On the body 20 is a suitable locking device 20^a by which the tube is locked to the body to hold the wing in the desired angular position. 15 Suitable means, not herein shown, operatively connect the body 1 of the car with the rear side of the wing 14 whereby the wing may be swung about the wing post away from or toward said car body.

20 The skeleton body of the wing is formed to provide top and bottom parallel grooved guides or rails 23—24 which are inclined downwardly and outwardly at an angle to both the vertical and horizontal as best shown 25 in Fig. 2. Preferably I dispose the top guide or rail in that inclined plane that passes through the top inner and bottom outer corner of the wing as a whole. As the bottom guide or rail is parallel with the top one, it follows that the bottom guide or rail opens 30 through the bottom of the wing about midway between its ends. The portions of the skeleton frame at the bottom edge of the wing are connected together by an elongated 35 plate 25 secured at its ends to the rear face of said frame portions in any suitable manner. Thus, there is provided on the bottom of the frame an opening which communicates with a space 26 between said guides or rails.

40 It is pointed out at this time that the bottom inner corner of the wing is cut away as at 27 along a line parallel with the guides or rails 23—24. Associated with said cut away portion 27 on the front or outer side of the wing 45 is a shoe or blade 28 which is pivoted at its outer and narrower end to the wing as at 29. On the rear side of said shoe, near its inner and wider end is fixed one end of an arcuate bracket 30. Said bracket is concentric with 50 pivotal axis 29 and its other end overhangs the plate 16^a on the rear side of the skeleton body or frame 15. In said bracket is formed a plurality of spaced openings 31 to register with a hole provided therefor in the wing, a pin 31^a being inserted through the registering holes to secure the shoe in proper position with respect to the wing.

55 32 indicates as a whole a substantially pointed element or casting which will be hereinafter referred to as a ditching blade carrier plate. Said element comprises a body 33 having a substantially horizontal hollow bottom portion 34 divided off into chambers or compartments by longitudinally spaced, 60 vertically disposed walls 35. Said element

also has top and bottom, parallel inclined portions 36 and 37 respectively disposed at an angle to said bottom portion and which project beyond the wider end of the body portion 33 in which is formed a pocket 38 as 70 best shown in Fig. 8. The inclined portions 36 and 37 bear the same angular relation to the hollow bottom portion of the carrier plate as the guides or rails 23—24 bear to the bottom portion of the wing and said portions 36—37 are formed for sliding guided movement within and longitudinally of said guides or rails.

75 39 indicates a ditching blade having vertically spaced top and bottom portions 40 and 41 of different lengths and inner and outer inclined end portions 42 and 43 respectively as best shown in Fig. 6. In the top portion of the ditching blade are longitudinally spaced notches 44 dividing said top portions 80 into tongues 45. The top portion of the blade fits into the bottom portion of the carrier plate and when so fitted the tongues 45 extend into the compartments 34 thereof and the notches 44 receive the walls 35 after 90 which said portions of the carrier plate and blade are riveted or bolted together in any suitable manner. When the ditching blade is secured to the carrier plate 33, the inclined end or edge portions 42 form a continuation 95 of the plate portion 37, while the ditcher blade as a whole, defines the maximum cross sectional area of the widest and deepest ditch that can be made thereby.

100 Connecting the inner end parts of the guides or rails 23—24 is an open like frame 46 in which is journalled in a plane between, but parallel with said guides or rails, a rotative nut 47 suitably held against endwise movement. Operatively engaged in said nut is a 105 screw threaded rod 48 having its outer end formed to provide a circular flat head 49 that engages in the pocket 38 of the carrier plate. In said head is an elongated opening 50 through which a pin or bolt 50^a extends to 110 operatively connect said rod to the carrier plate with a limited amount of play or lost motion between them. The purpose of such play or lost motion will later appear.

115 On the rear face of the wing toward the inner top corner thereof is mounted a motor 51 of the reversible type. Said motor is preferably a pneumatic one and on its shaft is fixed a sprocket 52 which through a chain 53 drives a larger sprocket 54 fixed on one end of the nut 47. When the motor runs in one direction, it will turn the nut 47 to feed the rod 48, carrier plate 33 and ditching blade 39 outwardly and when said motor runs in the other direction it feeds the rod carrier plate and ditching blade inwardly. In this manner the ditching blade may be projected or retracted along the guides or rails 23—24. The motor 51 of course is controlled from the cab 8 through suitable means disposed there- 120 125 130

in and conduits 51^a leading thereto from said motor.

In connection with the main wing 14 is a secondary wing 55 hereinafter termed an extension wing or bank shaping and material carrying wing for the reason that it is so connected to the main wing as to be employed either as an extension of the main wing or when moved into different angular positions with respect thereto may be employed to shape up a bank or to carry material forwardly to fill in cuts and hollows. The wing 55 is pivoted at 56 to a plate 57 which in turn is pivoted to the outer bottom corner of the main wing to swing about a horizontally disposed axis 58. The top edge of said plate 57 is made concentric with the pivotal axis 58 and extends under an arcuate flange 59 on the front face of the main wing. In said flange 20 and associated portion of the plate 57 are openings through the desired registering ones of which a pin 60 may be inserted to lock the plate in the desired angular relation upon the main wing. When the wing 55 is disposed in the plane of the wing 14, it may be swung about the pivot 58 into different angular positions with respect thereto by means of a double acting cylinder 60' disposed on the top edge of the wing 14. The piston rod 61 of said cylinder is operatively connected to a cross head 62 is slideable on a guide 63 also disposed upon the top edge of the wing 14. A link 64 is connected at one end to the cross head and is 30 detachably connected at its other end to the rear side of the wing 55. When air under pressure is admitted to the proper end of the cylinder 60', it is apparent that the wing 55 is positively swung up or down about the pivot 58. Said wing 55 is operatively connected at its rear side with the car body by means of braces, in the usual manner and not herein shown.

When it is desired to employ the wing 55 as a carrier wing, the braces just above mentioned are disconnected from the rear side of the wing and the link 64 is likewise disconnected therefrom. Thereafter the wing may be swung about the pin 56 into the desired position with respect to the car and is held in said position by means of a brace 65 on the standard 10, adapted for engagement with a coacting device 66^a in the front face near the outer end of said wing 55.

In Fig. 5 is illustrated a transverse cross section of a typical road bed construction wherein the breast 66 of the ballast slopes down to the horizontal berm 67. The outer edge 68 of the berm which defines one edge of the ditch 69 is spaced laterally from the rail 3 a certain specified standard distance, which distance must remain unchanged although such distance may vary upon different railroads.

The ditch 69 which also is of a standard

cross section, has oppositely sloping inner and outer side walls 70 and 71 respectively and a horizontal bottom wall 72, the bank 73 beginning at the outer edge of the ditch 69. As before mentioned, the edge 68 must conform as to distance from the rail by certain specification adopted by the railroad and the only deviation permitted is in case of passing about or around some insurmountable obstruction. As to the depth of the ditch, the same may be changed to meet the conditions at hand, but ordinarily the deeper the ditch, the wider it is made but still maintaining the inner edge of the ditch as before explained. In Fig. 5 I have shown the substantial maximum width and depth of the ditch in full lines and two smaller or more narrow and shallow ditch cross sections in dotted lines.

With the distance between the rail 3 and inner edge or line 68 of the ditch 69 known in advance, the wing 14 is swung outwardly away from the car body about the wing post until the outer end of the guide 24 coincides therewith. The motor 51 is then actuated to project the carrier 33 and ditching blade 39 outwardly the desired distance for the depth and width of the ditch to be made.

As the guides 23 and 24 are disposed in the angle corresponding to the angle of the inner side 70 of the ditch, it follows that when the ditching blade is projected, the edge 68 does not vary although the depth and width of the ditch increases in proportion to the rate of projection of the blade. Thus, to drain a certain locality adjacent a track, a shallow and narrow ditch is begun and by gradually projecting the ditching blade as the car proceeds, the ditch is made wider and deeper. Thus drainage from the ballast is taken care of and the water may be caused to flow along the ditch for disposal.

To ditch about an obstruction, the wing 14 is swung in toward the car so as to pass said obstruction. Thus as it is apparent by correctly positioning the wing 14 and then actuating the ditching blade, the ditch may be formed at any required distance from the rail and may be maintained except when necessary to pass around a large obstruction.

Of course, due to the nature of the work carried out, loose ballast material and the like is apt to accumulate upon the back of the wing and into the guide 24. However, with the play provided between the carrier plate 33 and rod 48 before described, this play permits of imparting small initial jerking movements to the carrier and blade to free it from binding when such material packs up thereon. These small jerking movements readily free the carrier plate and blade so that they may then be more readily and easily projected and retracted.

When it is desired to employ the wings 14 and 55 for ballast spreading and shaping op-

erations without ditching, the carrier and blade are retracted to that extent so that the bottom horizontal edge of the blade substantially coincides with the bottom edge of the wing 14.

With the improved construction, a general maintenance of the road bed is easily carried out and when ditches are necessary the same can be produced in the same operation along with spreading and shaping.

While in describing my invention I have referred in detail to the form, arrangement and construction of the various parts thereof, the same is to be considered as illustrative only so that I do not wish to be limited thereto except as may be specifically set forth in the appended claims.

I claim as my invention:—

1. A railway maintenance and construction car embodying therein a car, a spreader wing carried thereby for forming a portion of a road bed and a ditcher element mounted on the rear side of the wing for a projecting and retracting movement with respect to the bottom of said wing.

2. In combination with a spreader wing having a substantially horizontal bottom edge portion, a ditching blade, means on one side of said wing disposed at an angle to said bottom edge other than a right angle and providing a guide for said blade and means for projecting and retracting said blade along said guide, with respect to said bottom edge of the wing.

3. In combination with a spreader wing having a substantially horizontal bottom edge portion, a ditching blade, means on one side of said wing disposed at an angle to said bottom edge other than a right angle and providing a guide for said blade and means formed with a limited amount of play therein for projecting and retracting said blade along said guide with respect to said bottom edge of the wing.

4. In combination with a spreader wing having a substantially horizontal bottom edge portion, a ditching blade, means on one side of said wing disposed at an angle to said bottom edge other than a right angle and providing a guide for said blade, a screw threaded member carried by said wing and operatively engaged with said blade to move it in either direction along said guide.

5. In combination with a spreader wing having a substantially horizontal bottom edge portion, a ditching blade, means on one side of said wing disposed at an angle to said bottom edge other than a right angle and providing a guide for said blade, a screw threaded member operatively connected at one end to said blade, a nut in which the other end of said screw threaded member is engaged and means for turning said nut in either direction.

6. In combination with a spreader wing

having a substantially horizontal bottom edge portion, a ditching blade, means on one side of said wing disposed at an angle to said bottom edge other than a right angle and providing a guide for said blade and a screw threaded member carried by said wing and operatively engaged with said blade with a limited amount of lost motion therebetween for moving said blade in either direction along said guide.

7. In combination with a spreader wing, a pair of inclined parallel guide rails on one side of the wing and extending to the bottom of said wing and a ditching blade mounted for movement in said guides, said blade having an edge disposed in the plane of one of said guide rails.

8. In combination with a spreader wing, a pair of inclined parallel guide rails on one side of the wing and extending to the bottom of said wing, a ditching blade mounted for movement in said guide rails, a screw rod operatively engaged at one end to said blade, a rotative nut in which the other end of said rod is engaged, means on said wing providing rotative bearing for said nut though holding the same against endwise movement and means for turning said nut in either direction.

9. In combination with a spreader wing, a pair of inclined parallel guide rails on one side of the wing and extending to the bottom of said wing, a ditching blade mounted for movement in said guide rails, a screw rod operatively engaged at one end to said blade, a rotative nut in which the other end of said rod is engaged, means on said wing providing rotative bearing for said nut though holding the same against endwise movement, a reversible motor mounted on said wing and operatively connected to said nut to turn it in either direction.

10. In combination with a spreader wing, a pair of spaced guide rails on the rear side of the wing and extending at their bottom ends to the bottom end of said wing, means connecting the bottom ends of said guide rails together, a ditching blade mounted for movement in said guide rails so as to be projected and retracted beyond said connecting means, a reversible motor on said wing and means connecting said motor and blade whereby the latter may be moved in either direction on said guide rails.

11. In combination with a spreader wing, a pair of inclined parallel guide rails on the rear side of the wing and extending at their bottom ends to the bottom end of said wing, a carrier slideable in said guide, a ditching blade operatively connected to said carrier and means for moving the carrier in said guide rails in either direction.

12. In combination with a spreader wing having a substantially horizontal bottom edge portion, a ditching blade mounted on the

rear side of the wing and means providing a guide on said wing for said blade and in which it is capable of movement in a plane parallel with that of the wing and other than that at a right angle to its bottom edge.

⁵ In testimony whereof I have hereunto set my hand this 18th day of April, 1929.
